VULCANIZING PRESS

Herman E. Morse, Akron, Ohio, assignor to Wing-foot Corporation, Wilmington, Del., a corporation of Delaware

Application June 29, 1932, Serial No. 619,857

8 Claims. (Cl. 18—17)

This invention relates to presses, and more particularly to vulcanizing presses for curing rubberized material, such as flat conveyor belting, together with means for stretching the rubberized material prior to the vulcanizing operation.

An object of the invention is to provide an improved vulcanizing press.

Another object of the invention is to produce a vulcanizing press having means for stretching the material prior to the vulcanizing operation, capable of producing a flat and excellent product which will not "grow" in service.

Another object of the invention is to provide stretching means which are in correct alignment with the material stretched.

Another object of the invention is to provide a vulcanizing press with stretching means which are mounted upon independent foundations so that the stretching operation is achieved without any mis-alignment of the press platens. This construction also acts to prevent deformation of the press platens with the resulting unequal pressure over the surfaces thereof.

Another object of the invention is to provide a vulcanizing press with independently mounted stretching apparatus, so that the vulcanizing press and particularly the ends thereof are easily accessible at all times.

Another object of the invention is to provide a vulcanizing press with material stretching means which are independent of the press, and to provide coordinating apparatus therebetween so that the movement of the press platens will cause a corresponding movement of the stretching means.

Another object of the invention is to provide hydraulic means for simultaneously moving the stretching means up and down in coordination with the movement of the press platens, so that the belt will be held away from the hot press platens when the vulcanizing operation is not in progress.

Another object of the invention is to provide mechanical means for coordinating the movement of the stretcher and vulcanizing press platens.

For a better understanding of the invention reference may now be had to the accompanying drawings, wherein:

Fig. 1 is a side elevation with a portion of the center thereof removed, illustrating the press and stretching mechanism embodying the present invention;

Fig. 2 is a plan view of the mechanism illustrated in Fig. 1;

Fig. 3 is a transverse cross-sectional view taken on line III—III of Fig. 1;

Fig. 4 is a transverse cross-sectional view taken on line IV—IV of Fig. 1;

Fig. 5 is a perspective view of the right end of the machine illustrated in Fig. 1;

Fig. 6 is a cross-sectional view taken on line VI—VI of Fig. 2;

Fig. 7 is a view taken on line VII—VII of Fig. 6;

Fig. 8 is a cross-sectional view taken on line VIII—VIII of Fig. 7;

Fig. 9 is a diagrammatic side elevation illustrating hydraulic means for coordinating the stretcher and press platens;

Fig. 10 is a side elevational view illustrating mechanical means for securing coordination between the stretcher and press platens; and

Fig. 11 is an end elevation of the mechanism shown in Fig. 10.

While the apparatus embodying the present invention can be employed in the manufacture of substantially any vulcanizable or heat treated article as will be understood, it is particularly adapted to vulcanize flat rubberized fabric conveyor belts. Accordingly the vulcanizing press has been illustrated and described in conjunction with conveyor belting.

Referring to the drawings, the vulcanizing press embodying the present invention comprises a base 15, to which an upper platen 16 is rigidly secured by a plurality of tie rods 17. Mounted upon the base 15 are a plurality of hydraulic motors 20, having pistons 21, which carry a lower platen 22. Mounted between the upper platen 16 and the lower platen 22 is an intermediate platen 23, which cooperates with the upper platen 16 to mold and vulcanize a belt 28. The lower platen 22 cooperates with the middle platen 23 to mold and vulcanize a belt 27. The three platens are brought together by an upward movement of the lower platen 22. The middle platen 23 is supported in a position intermediate of the upper platen 16 and the lower platen 22 by any suitable means when the press is open. Multiple platen presses of this general type are not new per se, and it is believed the general construction and operation thereof will be understood by those skilled in the art.

If the sides of the belt or belts are to be molded or shaped during the curing operation flat bars or plates are provided between the platens which can be moved in from the sides of the platens by wedge means to clamp on the sides of the belts. This apparatus is more or less well known in the art and forms no part of the present invention.

In order to insure flat stretched belts during the vulcanizing operation, and also to substan-

tially eliminate any future "growth" in the belt, stretching means are provided to stretch the belts prior to and during the curing operation. To this end clamping means are provided at one end 5 of the press platens to grip the upper belt 28, while stretching means are provided at the other end. With respect to the lower belt 27, the clamping means are provided at the end of the platens opposite that where the upper belt is 10 clamped, while the stretching means for the lower belt are provided at the clamping end of the upper belt. In the present invention the stretching means includes frames 30 and 31, which are mounted upon the base 15 independently of the 15 means 17 and 20 supporting the platens 16, 22 and 23 and which are secured at their upper ends to longitudinally extending channel irons 32. The frame 30 supports a clamping unit, indicated generally at 33, which is adapted to clamp on 20 one end of the lower belt 27.

Referring to Fig. 4, the clamping unit 33 includes a cross-head 35 which is slidably gibbed to the frame 30 by gib 36. Hydraulic motors 38 mounted upon the frame 30 control the vertical 25 position of the cross-heads 35, inasmuch as the piston rods 39 of the hydraulic motors 38 are secured to the cross-heads 35. A lower clamping jaw 41 is secured between the cross-heads 35 by any suitable means, such as pins 42. Mounted 30 upon the upper ends of the cross-heads 35 by tie rods 43 are hydraulic motors 44, the piston rods 45 of which extend down through suitable apertures in the upper end of the cross-heads 35 and which serve to carry an upper clamping jaw 46 35 which cooperates with the lower clamping jaw 41 to clamp the belt 27 therebetween.

Small auxiliary hydraulic motors 50 having piston rods 51 are secured to the tops of the motors 44. The piston rods 51 of the hydraulic motors 40 50 are provided with spreaders 52, to the ends of which are secured tie rods 53, which extend 55 down through the tie rods 43 fastening the hydraulic motors 44 to the cross-heads 35 and which are secured at their ends to the upper 60 clamping member 46. The hydraulic motors 44 will thus serve to clamp the upper jaw member 46 against the lower jaw 41, while the hydraulic motors 50 will serve to move the upper jaw 46 upwardly when it is desired to unclamp or release the belt.

In order to have the same movement at all 65 times at both ends of the lower jaw member 41, and to thus maintain it perfectly horizontal, racks 57 (Fig. 1) may be secured to the sides of the frame 30, which racks cooperate with pinions 58 carried upon the ends of a shaft 59, which is journaled at its ends, in suitable bearing plates 60 secured to the cross-heads 35. In this manner the cross-heads 35 and the lower clamping 65 jaw 41 will be level at all times regardless of their vertical position.

At the same end of the vulcanizing press as the unit 33 for clamping the end of the belt 27 is a unit indicated generally at 65 for clamping on and stretching the upper belt 28. Referring to Figs. 1 and 3, the clamping and stretching unit 65 includes frames 66 mounted upon the base 15 and secured at their upper ends to the channels 70 32, which frames 66 slidably support cross-head members 67 through the agency of gib 68. Hydraulic motors 70 having piston rods 71 are mounted upon the frames 66 and control the vertical position of the cross-heads 67, inasmuch 75 as the piston rods 71 of the hydraulic motors 70

are secured to the lower sides of the cross-heads 67.

The vertical positions of the cross-heads 67 may be kept the same through the agency of racks 73 secured upon the frame 66, which racks co-operate with pinions 74 carried upon a shaft 75 journaled in suitable brackets 76 secured to the cross-heads 67. This mechanism is similar in design and function to that described above with respect to the means for synchronizing the movement of the cross-heads 35 of the clamping unit 33.

Slidably mounted in suitable grooves 80 in the cross-head members 67 is a lower clamping member 81. Secured to the lower clamping jaw 81 at the ends thereof are frame members 82 to which are secured hydraulic motors 83, which in turn support hydraulic motors 84. The hydraulic motors 83 have pistons 86, which extend down through suitable apertures 87 in the members 82, and which are secured to an upper clamping jaw 90. The hydraulic motors 84 have piston rods 92, which are secured to their ends to spreaders 93 carrying tie rods 94, which extend down and are secured to the upper clamping jaw 90. In this manner the hydraulic motors 83 serve to move the clamping jaw 90 downwardly against the clamping jaw 81, while the hydraulic motors 84 serve to raise the jaw 90 away from the jaw 81 when it is desired to unclamp or release the belt 28.

The horizontal position of the clamping jaws 81 and 90, the frame members 82, and the hydraulic motors 83 and 84, is controlled by a pair of hydraulic motors 96, the piston rods 97 of which are secured to the clamping jaw 81. The cylinders of the hydraulic motors 96 are secured by suitable tie rods 98 to the cross-heads 67.

In order that the cross-heads 35 and 67 can be moved vertically while the belts are under tension between the various clamping means holding the same, a plurality of roller bearings 101 and 103 are provided along one side of the frames 30 and 66, which cooperate with a laterally extending flat portion of the cross-heads, so that a smooth sliding action will be obtained even with considerable tension on the belts 27 and 28.

Racks 105 are provided on the cross-head 67, which racks cooperate with pinions 106 carried upon a shaft 107, journaled in suitable brackets, secured to the frame members 82 that are mounted upon the lower clamping jaw 81. This mechanism serves to unify the operation of the hydraulic motors 96 and insures that the jaw members 81 and 90 move in and out at both sides thereof of equal distances.

At the other end of the press, upon the framework 31, is mounted a clamping unit indicated generally by the numeral 110, which serves to clamp the end of the belt 28 and thus cooperate with the clamping and stretching unit 65. Co-operating with the clamping unit 33 is a clamping and stretching unit which is indicated as a whole at 115, and which is mounted upon a suitable frame 118 secured to the base 15 and channel iron 32. The units 115 and 110 are exactly similar to the units 33 and 65, except that they are placed at the other end of the belt and that the stationary clamping unit 110 is placed above the 145 clamping and stretching unit 115. Accordingly the various elements forming the clamping unit 110 and the clamping and stretching unit 115 are designated with the same numerals which indicate similar parts in the clamping unit 33 and 150

the clamping and stretching unit 65, except that the suffix *a* has been added.

The various hydraulic motors employed in the apparatus are connected in any suitable manner to an adequate source of hydraulic pressure. To this end, conduits 120, 121, 122, 123 and 124, valved as hereafter described, extend to hydraulic motors 70, 38, 20, 38^a and 70^a. Conduits 126 and 127 are connected to the motors 44, 83, 44^a, 83^a and 50, 84, 50^a and 84^a respectively by way of swivel connections 128 and 129. Hand valves (not shown) control the passage of fluid through the conduits, the valves being placed in a convenient position for operation. The motors 96 and 96^a are provided with fluid pressure by means of swivel connections 116 extending from two way valves 117 connected to supply conduits 118.

The movements of the platens 22, 23 and 16 are adapted to be coordinated with the vertical movements of the clamping and the clamping and stretching units 33, 65, 110 and 115, and this can be accomplished by either mechanical or hydraulic means. The diagrammatic showing of Fig. 9 indicates how this can be accomplished through hydraulic means. Fig. 9, for the sake of simplicity, only illustrates two platens of the press and also illustrates only one belt employed in conjunction therewith, together with one set of clamping and clamping and stretching units. The coordinating movement of the platens and the clamping and stretching units is achieved by providing a two way valve 130, which is secured to any fixed part of the frame of the apparatus. An inlet pipe 131 extends from the valve to any suitable supply of hydraulic pressure. A plunger 132 projecting above the valve 130 will, when depressed, allow the hydraulic pressure in the pipe 131 to flow through the valve 130 to the conduit 121, which extends to the hydraulic motors 38, which control the vertical movement of the clamping unit 33. Another plunger 136 is provided upon the valve 130 and which when depressed allows the hydraulic fluid or pressure in the conduit 121 to flow to the atmosphere by way of an exhaust conduit 137. A post 139 is provided upon the upper side of the valve 130 and serves to pivotally support a rocker arm 140, which has a pair of adjustable tappets 141, which contact with the plungers 132 and 136. The end of the rocker arm 140 is secured by a suitable link 143 to the end of a bar 144, which is pivotally supported as at 145 upon a suitable upright 146, which is fastened to the movable platen 22. The other end of the bar 144 is pivotally secured, as at 148, to an upright 149 fastened to the cross-head of the clamping unit 33. The operation of this coordinating mechanism is as follows:

Assuming the operator has clamped upon a section of belt to be vulcanized and has stretched the same, and thereafter desires to close the platens 22 and 23 of the press together; he will now open a hand valve, which controls the flow of fluid pressure to the hydraulic motors 20 and the platen 22 of the press will start upward. As soon as the platen 22 of the press begins to move upward the upright 146 will cause an upward movement of the bar 144 about the pivot 148, thus tilting the rocker arm 140 due to the connection through the link 143. The tilting of the rocker arm 140 will compress the plunger 132, which will allow fluid pressure to flow through the conduit 131, the valve 130, and conduit 121 to the hydraulic motors 38, which will cause an upward movement of the clamping unit 33. Thus the upward movements of the platen 22 and

clamping unit 33 will be practically simultaneous. As soon as the platen 22 has clamped the belt 27 against the platen 23, it will have reached the top of its travel and further movement of the clamping unit 33 will cause the bar 144 to pivot about the point 145, thus tipping the rocker arm 140 in the opposite direction to allow plunger 132 to rise and at the same time to depress plunger 136, allowing the hydraulic pressure in the conduit 133 to escape by way of the outlet 137. As soon as the hydraulic pressure has been sufficiently reduced, the clamping unit 33 will drop back very slightly to bring the rocker arm 140 substantially horizontal, in which position there will be no movement of the clamping unit 33, which will be substantially on a level with the platens 22 and 23. Thus during the vulcanizing operation the belt 27 will be held flat and smooth between the platens 22 and 23, and at the same time will be on the same horizontal plane at both the clamping unit 33 and in the press.

After the vulcanizing operation the operator will open the valve controlling the exhausting of the hydraulic motors 20, which will cause the lower platen 22 to begin to move away from the upper platen 23. The downward movement of the platen 22 will cause the rocker arm 140 to tip to the right to depress the plunger 136, thus allowing the fluid under pressure in the hydraulic motors 38 to escape to the atmosphere through the conduits 121 and 137. The clamping unit 33 will then fall practically simultaneously to the movement of the platen 22. However, once the platen 22 has reached the bottom of its travel continued movement of the clamping unit 33 will bring the rocker arm 140 to the horizontal position which will cause the closing off of the exhaust from the hydraulic motors 38 to stop further movement of the clamping unit 33. The operator may now open the valve controlling the clamping of the jaws upon the belt and pull the vulcanized section of the belt on through the press.

From the foregoing it is believed apparent that the coordinating operation of the clamping unit and the platens will be understood. Accordingly the coordinating operation of the clamping and stretching unit 115 (shown in Fig. 9) with respect to the movements of the platen will not be explained in detail, inasmuch as this movement is the same as that described above with respect to the clamping unit 33. The operation of the co-ordinating means has been described in conjunction with a single pair of platens and a single belt, for the sake of simplicity. However, the adaptation of coordinating means such as described above to the remaining clamping unit 110 and the clamping and stretching unit 65 of the duplex press, will be readily apparent.

The movements of the clamping units and the platens can be coordinated by mechanical means, if so desired. Suitable means for accomplishing this result are indicated in Figs. 10 and 11, and comprise a rack 150 secured to the movable platen 22, which cooperates with a pinion 151 secured upon a shaft 152, journaled in suitable brackets 153 upon a frame 154, which slidably supports the clamping and stretching means 115. A pair of racks 157 are secured to the clamping and stretching means 115 and these racks cooperate with pinions 158 mounted upon the shaft 152 so that vertical movement of the platen 22 will cause a corresponding vertical movement of the clamping and stretching unit 115.

To assist in holding the belts 27 and 28 in the stretched positions during the vulcanizing opera-

tion, suitable locking means may be provided to lock the stretching means in the extended or stretching position so that undue strain upon the stretching mechanism will be obviated. Locking means of this type will be employed on the stretching units 65 and 115. The locking mechanism is similar upon the two stretching means. However the locking mechanism on the stretcher 115 has been selected for illustration and is shown in Figs. 6, 7 and 8. The locking mechanism comprises blocks 160^a secured upon the cross-heads 67^a, which blocks are provided with an indenture 161^a which is adapted to cooperate with lock bars 162^a, which are slidably carried upon the members 82^a. One of the members 82^a carries a post 165^a, upon which is pivotally mounted a rocker arm 166^a, which is pivotally secured as at 167^a to the lock bar 162^a. The other of the members 82^a has a post 169^a to which is pivotally secured a link 170, which is pivotally secured as at 171^a to the other of the lock bars 162^a. A link 174^a is pivotally secured as at 175^a to the bar 170^a, and at its other end is pivotally secured as at 176^a to the rocker arm 166^a. A bar 177^a is pivotally fastened, as at 178^a to the rocker arm 166^a and is provided with a handle 180^a and with a notch 181^a, whereby the bar 177^a can be pulled over a pin 182^a mounted upon the member 82^a. Springs 185^a are provided adjacent the lock bars 162^a and will serve to normally retain the lock bars 162^a in the innermost or locking position. The locking bars 162^a can be moved and held to the non-locking position by pulling the handle 180^a to bring the notch 181^a into engagement with the pin 182^a. Similar locking mechanism may of course be provided upon the stretching unit 65.

The operation of the apparatus is as follows: Generally the belts 27 and 28 are made up in such long flat sections it is impossible to vulcanize more than a short section thereof at one time, the remaining portions of the belts being rolled up upon themselves. Now assuming that a section of the belts has just been vulcanized and that the press has been opened and the clamping and stretching means loosened, then the belts are moved longitudinally, in opposite directions, so that new unvulcanized sections of the belts are brought between the platens 16, 22 and 23. The operator will now energize the clamping units 33 and 110, which is accomplished by supplying fluid under pressure to the hydraulic motors 44 and 44^a, thus causing a downward movement of the piston rods 45 and 45^a to clamp the belts 27 and 28 between the jaws 46 and 41 and the jaws 46^a and 41^a. The hydraulic motors 83 and 83^a are energized simultaneously or shortly after the operation of the hydraulic motors 44 and 44^a. The operation of the hydraulic motors 83 and 83^a causes downward movement of the piston rods 86 and 86^a to clamp the belts 27 and 28 between the jaws 90 and 81 and the jaws 90^a and 81^a.

The stretching cylinders 96 and 96^a are now operated to cause an outward stretching movement of the jaws 90 and 81 and 90^a and 81^a. After the belts 27 and 28 have thus been stretched between the units 33 and 115 and the units 110 and 65, respectively, the operator is ready to close the press. To do this he opens the valve (not shown) which allows fluid under pressure to flow to the hydraulic motors 20, which will cause the platens 22 and 23 to begin their upward movement. The coordinating means causing simultaneous movement of the various units 33, 65, 110 and 115 with the movement of the platens, which has been described above, will now cause a

simultaneous upward movement thereof together with the platens. After the platens have come together, steam or other curing medium will be passed to the platens and the vulcanizing operation will take place.

When the press is opened upon the completion of the vulcanizing operation, the movement of the various parts is substantially a reverse of that of the closing of the press. The various units will move down with the platen in coordinating relation therewith. Prior to the opening of the clamping jaws, the operator will relieve the stretching tension, which will be accomplished by pulling the handles 180 and 180^a so that the notches 181 and 181^a will cooperate with the pins 182 and 182^a to lock the lock bars 162 and 162^a in the retracted position. The pressure in the hydraulic motors 96 and 96^a will now be relieved to allow the inward movement of the stretching means, thus relieving the tension on the belt. The operator will now open the interior of the hydraulic motors 44 and 44^a and 83 and 83^a to the atmosphere and will then pass fluid under pressure to the hydraulic motors 50 and 50^a and the motors 84 and 84^a, which will cause the upward movement of the piston rods 51 and 51^a and the piston rods 92 and 92^a, which will in turn raise the jaws 46 and 46^a and the jaws 90 and 90^a, to cause an unclamping or a release of the belts 27 and 28. The vulcanized portions of the belts 27 and 28 can now be moved out from between the platens and new unvulcanized sections of the belts will be brought beneath the platens, whereupon the operation can be repeated.

By the present invention a vulcanizing and stretching press has been provided in which the stretching mechanism is entirely distinct from the vulcanizing means, although coordinated therewith, so that there will be no stresses tending to mis-align the platens, and, moreover, the press, as well as the stretching means, will be easily accessible from all sides and from the ends. The vertical movement of the clamping and stretching units has been coordinated with the vertical movement of the platens so that at all times the platens and the clamping and stretching units will be substantially on the same horizontal level, insuring a smooth straight stretch. Means have been provided to maintain the belt in a stretched condition without tension upon the stretching units. Suitable mechanism has also been employed to insure the uniform outward and vertical movement of all moving parts of the apparatus so that no curved or mis-shaped belts will be produced.

While the apparatus has been illustrated and described as comprising a three platen press, it will be apparent that the invention is not limited in this respect, the various features thereof being readily adaptable to two platen presses, or even to presses having more than three platens. The coordinating mechanism for coordinating the movement of the clamping means and the platens can be either fluid pressure means, or mechanical means.

While the various motors for operating the movable portions of the apparatus have been described as hydraulic motors, operating by hydraulic pressure, it will be obvious that such motors may be of any type operated by any fluid pressure means, either liquid or gas.

The belts 27 and 28 are preferably moved through the press in opposite directions thus placing the stretching units 65 and 115 at opposite

ends of the press. However this procedure and construction obviously need not be followed as the belts can be moved through the press in the same direction. Again the belts or other material molded and heat treated in the press can be of any size and need not be of such a length that they must be vulcanized in sections. Thus individual pieces or lengths just long enough to be gripped and stretched can be handled.

10 It will be understood that the apparatus comprising the present invention can be employed to mold and heat treat substantially any elongate article and that the description and drawings show it employed in the vulcanization of 15 rubber conveyor belting by way of example only although the apparatus is particularly adapted for that purpose.

Although I have illustrated and described only 20 one preferred form which the invention may assume, and have described that form in detail, it will be apparent to those skilled in the art that the invention is not so limited but that various modifications may be made therein without departing from the spirit of the invention or from 25 the scope of the appended claims.

What I claim is:

1. A vulcanizing press comprising three associated platens positioned to form two material treating stations, means for moving said platens 30 to and away from each other, stretching means associated with each material treating station for stretching and holding the material to be vulcanized flat and smooth during the vulcanizing operation, each of said stretching means including 35 two pair of relatively movable clamps and means positioned at opposite ends of the platens for moving one of the pairs of clamps of each stretching means.

2. A press for vulcanizing belts comprising three 40 superimposed platens, the lower and middle platens molding one belt and the middle and upper platens molding a second belt, a belt stretching means for each belt, each of said means including clamps mounted independently of the platens 45 for clamping on the belt at the ends of the platens, means mounted independently of the platens for moving one of the clamps relatively away from the other to stretch the belt held therebetween, said clamp moving means being mounted at opposite 50 ends of the platens, means for moving the platens together, means for controlling the vertical position of the clamps, said last named means being coordinated with the movement of the platens 55 so that the belts will be maintained in a horizontal position and in proper alignment at all times.

3. A press for vulcanizing belts comprising three superimposed platens, the lower and middle platens molding one belt and the middle and upper 60 platens molding a second belt, a belt stretching means for each belt, each of said means including clamps mounted independently of the platens for clamping on the belt at the ends of the platens, means mounted independently of the platens for 65 moving one of the clamps relatively away from the other to stretch the belt held therebetween, means for locking said clamps in the stretching positions, said clamp moving means being mounted at opposite 70 ends of the platens, means for moving the platens together, means for controlling the vertical position of the clamps, said last named means being coordinated with the movement of the platens so that the belts will be maintained in a

horizontal position and in proper alignment at all times.

4. A press for vulcanizing belts comprising three superimposed platens, the lower and middle platens molding one belt and the middle and upper 80 platens molding a second belt, a belt stretching means for each belt, each of said means including clamps mounted independently of the platens for clamping on the belt at the ends of the platens, means mounted independently of the platens and at opposite ends thereof for moving one of the clamps relatively away from the other to stretch the belt held therebetween and means for moving the platens together.

5. A press for vulcanizing belts comprising three superimposed platens, the lower and middle platens molding one belt and the middle and upper 85 platens molding a second belt, a belt stretching means for each belt, each of said means including clamps mounted independently of the platens for clamping on the belt at the ends of the platens, means mounted independently of the platens for moving one of the clamps relatively away from the other to stretch the belt held therebetween, means for locking the clamp-moving means in 90 the stretching position to relieve strain thereon, means for moving the platens together, and means for controlling the vertical position of the clamps.

6. A press for vulcanizing belts comprising superimposed platens adapted to mold a plurality 105 of belts, a belt stretching means for each belt, each of said means including clamps mounted independently of the platens for clamping on the belt at the ends of the platens, means mounted independently of the platens for moving one of the clamps relatively away from the other to stretch the belt held therebetween, means for moving the platens together, fluid pressure means for controlling the vertical position of the clamps, valves 110 for the supply of fluid to said last named means, and mechanical means coordinated with the movement of the platens to control the operation of the valve so that the belts will be maintained in a horizontal position and in proper alignment 115 at all times.

7. In combination, a pair of platens adapted to mold and heat treat material, means to move the platens relatively to and from each other, means for stretching and holding the material during the molding and heating operation, fluid pressure 125 means for moving the stretching means in the same direction as the platens and mechanical means controlled by the position of the platens for controlling the supply of fluid pressure to the stretcher moving means, said mechanical means 130 coordinating the movement of the platen and stretcher moving means whereby the material will be held in the proper position at all times.

8. A press for vulcanizing rubberized belts including platens and means for stretching and 135 holding a belt between the platens in smooth flat condition during the cure, said stretching means including two pair of clamping jaws extending transversely of the belt, means for moving said jaws into clamping position, means controlling 140 the vertical position of said clamping jaws, one of said pairs of jaws being mounted for horizontal sliding movement, means for moving said last named pair of jaws horizontally to stretch the belt, and means for locking the jaws in the belt 145 stretching position thereof.

HERMAN E. MORSE.
